UNITED STATES PATENT OFFICE.

FREDERICK W. POPE, OF LYNN, AND GEORGE HENRY FOX, OF BOSTON,
MASSACHUSETTS.

MACHINE FOR MOLDING BOOT AND SHOE SOLES.

SPECIFICATION forming part of Letters Patent No. 268,124, dated November 28, 1882.

Application filed September 25, 1882. (No model.)

To all whom it may concern:

Be it known that we, FREDERICK WILLIAM POPE and GEORGE HENRY FOX, citizens of the United States, residing at Lynn and Boston, in the counties of Essex and Suffolk, respectively, and State of Massachusetts, have invented certain new and useful Improvements in Molding-Machines for Boot and Shoe Soles; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to a class of machines for molding boot and shoe soles, in which a set of soles deposited in a pile upon a suitable table are automatically fed to and afterward discharged from the molding-platens.

Our present improvements consist, first, of means for determining automatically the exact position of each sole as it is advanced between the molding-platens by the feed-plate, this portion of our improvements consisting in a pair of vibrating bars disposed upon the operating-table of the machine upon opposite sides of the feed mechanism and the lower or stationary molding-platen, such bars being pivoted adjustably to the table at their outer or rear ends, and with their opposite or free ends adapted to approach or recede from the ends of the lower molding-platen, in order to provide guides or stops against which the heel and toe of each sole as it is fed forward over such lower platen abut, the free ends of said bars being crowded toward each other over the lower platen, each by a connecting-rod, which connects it with an oscillating lever pivoted centrally to the table in rear of the feed-plate, the pivots which connect such rods with said lever being disposed upon opposite sides of the pivot of the latter in order that when this lever is turned in one direction the two bars are caused to simultaneously approach each other, while a spring suitably applied serves to force them together as the sole is fed to the platen. The lever is actuated to expand the bars by a stud from the feed-plate wiping against an inclined plane upon one edge of such lever, while

this lever and the bars before named are returned or closed by the spring.

Our improvements consist, secondly, of means for grasping and firmly holding each sole in position over the lower or stationary platen after the guide-bars have receded from the ends of such sole and while the upper platen is descending, this portion of our improvements consisting in yielding or spring-impelled clamp-pins contained within pockets in the bearing-face of each platen and adapted to clamp the sole between them as the upper platen descends, these clamp-pins as the platens meet receding and burying themselves in their respective pockets flush with the face of the platen, in order to present an even surface to act upon the sole.

Our improvements consist, thirdly, of means for adapting the gage-plate (which governs the passage of each sole to the lower platen) to vary the width of the throat which permits of the passage of soles to receive soles varying considerably in thickness, the same consisting in beveling the lower edge of such plate, whereby the throat through which the sole passes is made tapering vertically to such an extent that its height at its narrowest point is practically equal to the thickness of the thinnest sole, while its height at its widest point is equal to or slightly greater than the thickness of the thickest sole. Under these circumstances the thinnest sole has free unobstructed passage through the throat, while the thick sole makes a passage for itself by crowding against the bevel of the gage-plate and lifting the latter.

Our improvements consist, fourthly, in the combination, with a machine of the class named, of a vibrating finger adapted, as each sole is discharged from the lower platen after being molded, to tilt such sole into an upright position and pack it against those already stacked, the construction and operation of this finger being hereinafter explained.

The drawings accompanying this specification represent, in Figure 1, a side elevation, in Fig. 2 a rear end elevation, and in Fig. 3 a vertical longitudinal section, of the molds and clamp-pins of a machine embodying our improvements; Fig. 4, a plan of the automatic feed and mechanism connected therewith; Fig. 5, a front view of receiving-table and vibrating

finger; Fig. 6, a cross-section through gage seed-plate; Fig. 7, a perspective view of end of vibrating bars; Fig. 8, a section on line $x'x'$ of Fig. 2; Fig. 9, a section on line $y'y'$ of Fig. 8.

5 In the above-named drawings the frame of the machine is shown as composed of two upright side standards or housings, A A, suitably stayed by transverse cross bars or rods.

10 B represents the operating-table of the machine, which spans the housings A A at front and is preferably placed at an angle of forty-five degrees to the horizon, sloping downward at rear, this table supporting the "set" of soles to be molded.

15 C represents a frame spanning the front of the housings and preferably placed at an angle of forty-five degrees with the horizon, in order to be at right angles with the table B, this frame extending above said table.

20 B" in the drawings represents a horizontal shaft, mounted in suitable bearings in the housings A A and transversely of the machine, such shaft being supplied with the ordinary driving and loose pulleys. Upon one end of the shaft 25 B" we secure a pinion, D, which engages and drives a spur-gear, E, fixed upon one end of a second horizontal rotary shaft, G, situated alongside the shaft B" and parallel with it, and, like the latter, mounted in bearings in the 30 housings A A, this latter shaft, G, carrying near its center a crank, H.

35 M in said drawings represents a connecting-rod, one end of which is pivoted to the wrist of the crank H, while the other is pivoted to the knuckle of a toggle-joint composed of two links, I I', one of which—the upper one, I—is pivoted at its upper end to a stationary horizontal cross-bar, l², which spans and connects the upper parts of the housings A A, while 40 the lower link, I', is pivoted at its lower end to a cross-head, J, making part of a reciprocating frame, the remainder of this frame being composed of two parallel rods, L L, sliding in bearings L' L' in the housings, and 45 united at their upper ends by a cross-bar, L².

The customary two platens whereby a sole is molded are shown in the drawings, the upper one at M and the lower one at N, the latter being stationary and secured to the cross-bar l², before named, while the upper and movable platen is secured to the cross-bar L² of the movable frame before named.

50 The cross-head L² slides upon the rods L L, and coiled springs b b are interposed between such cross-bar and nuts screwed upon such rods, the stress of the springs b b, which may be regulated by the nuts, serving to determine the degree of pressure exerted by the upper platen upon the sole.

55 60 In carrying out our improvements we dispose upon the top of the table B and upon opposite sides of the center thereof, twin bars O P, the rear end of each being pivoted, as shown at e, to an adjustable stud, d, contained 65 within an inclined slot, e, created in the rear part of the table B, this adjustable stud hav-

ing a suitable clamp screw or nut, whereby it may be screwed to said table at any point in said slot. The front ends of the bars O P extend beyond the front edge of the table B and terminate in curved or concave bearers or stops f f, these bearers being disposed opposite the ends of the lower platen, N, and slightly above the upper surface of said platen, each bearer or stop having a ledge, g², upon its outer edge, against which the outer corners of the sole bring up as the latter is fed outward.

70 75 80 85 90 95 100 105 110 115 120 125 130 With extreme variation in size of soles the positions of the bearers f f in relation to the platen must necessarily vary, both laterally and longitudinally of the table B, and to effect this we employ the slots e e and adjustable pivots c c, before named. For instance, in changing from children's to women's numbers, the pivots c c would be moved outward in the slots e e, which slope downward toward the edges of the table B. This act carries the bearers f f laterally of the machine, away from the lower platen, to allow for the increased length of the latter, and of the soles to be molded upon it, and at the same time lowers the bearers to accomodate the increase in width of said platen and soles, while at the same time the pivots connecting the pitmen with said bars must be changed, a series of holes in said pitmen enabling this to be done.

100 105 110 115 120 125 130 To actuate the free ends of the bars O P and the bearers f f, we employ with each bar a pitman, n n, the outer ends of which are pivoted to the bars O P at their rear parts, while the inner ends of these pitmen are pivoted to opposite ends of a shipper-lever, i, situated centrally of the table B and over the feed-plate, to be explained, the pivot j of such lever being midway of the two pitmen, and erected upon said table in rear of said plate. Swinging the lever i upon its pivot j in one direction tends to crowd the bearers f f apart away from the immediate vicinity of the platen, and affords ample space for passage of a sole over and upon such platen. The lever i is crowded in the opposite direction and restored to its normal position in alignment with the longest plane of the table B, and the bearers f f caused to approach each other to their fullest extent or closed by a spring, k, one end of which is secured to the table B and the other to the rear end of the lever i.

120 125 130 To confine each sole firmly in position over the lower platen, while the upper platen is descending, after the position of such sole has been adjusted by the bearers f f, we employ a series of clamp-pins, l l, &c., m m, &c., which are contained in pockets o or p, formed respectively in the adjacent faces of the two platens and opposite each other, each pin being crowded outward beyond the face of the platen to its extreme position by a spring, q, contained within the pocket, and the two sets of pins, when the upper platen is at its highest point, standing sufficiently apart to permit of ready introduction of a sole between them. As the

upper platen completes a portion of its descent toward a sole upon the pins of the lower platen the upper pins, *m*, abut against such sole. Hence the two series of pins clamp the sole tightly in position between them while the upper platen completes its descent. As the two platens meet and mold the sole between them, the two series of pins recede into their pockets flush with the faces of said platens.

10 As the upper platen, after the molding of the sole has taken place, rises the two series of pins protrude from opposite directions, and free the sole from contact with the platens and permit it to readily drop from the pins of the lower platen when the upper die reaches a sufficient elevation.

To adapt or adjust the gage-plate before named to soles of varying thickness in the same set, we proceed as follows: Such gage-plate 20 is shown at *r* as a flat plate deposited upon the top of the frame *C*, and confined thereto by guides in which it freely plays vertically, the lower edge of this plate standing above the top of the table *B* a distance sufficient to 25 provide a narrow longitudinal throat, *s*, for passage of soles. The lower edge of the gage-plate *s* is beveled, as shown as *t*, in order that the front of the throat *s* shall be deeper than the rear thereof, as shown in Fig. 6 of the accompanying drawings. The rear termination 30 of the throat *s* is of a height equal to or slightly greater than the thickness of the thinnest sole of the set to be molded, while the front boundary of such throat is of a height slightly greater 35 than the thickness of the thickest sole of such set. Under these circumstances the thin sole will be pushed through the throat without trouble, the friction of the sole next above it against the bevel *t* preventing the latter sole 40 adhering to and following the first. The thick sole, when fed forward, wipes against the bevel *t*, pushes plate *r* aside or upward, and forces a passage through the throat *s*, the remainder of the soles in the pack being held back by the 45 body of the plate, as usual.

To fold or deposit each molded sole in succession upon those previously discharged from the platens, we proceed as follows: *Q* in the drawings represents a flat tablet or shelf, secured to the upper part of the machine-frame and in the same plane with and constituting practically, if not literally, a continuation of the table *B*, an orifice or slot, *R*, being formed in this shelf opposite the throat *s* to permit of passage 50 of soles to the platen *N*. We create centrally in the shelf *Q* a slot, *u*, which is in alignment with the longest plane of the machine, and at the front termination of this slot we erect a ledge, *v*, which is mounted adjustably upon 55 the shelf.

In connection with the shelf *Q* and ledge *v* we employ a swinging arm, *w*, the lower end of which is pivoted to a hanger depending from the said shelf, the arm *w* being actuated by a 60 connecting-rod, *x*, one end of which is pivoted to the said arm and the other to the upper arm

I, of the toggle-joint before named. As the arm *w* swings in arbitrary paths of motion, and as the pack of molded soles increases to the extent of one additional with every vibration of the arm, it follows that means must be employed to dispose of the pack as it accumulates. To effect this we connect the ledge *v* with the shelf *Q* by a thumb-screw, *u'*, which we screw down to an extent sufficient to induce a friction between the ledge and shelf that shall sustain the pack and yet be overcome by the arm *w* as it adds a new sole to the pack; or a plate-spring may be placed between the thumb-screw and shelf for the same purpose. In one extreme of movement the packing-arm *w* protrudes through the shelf *Q* and stands practically at right angles to the top of the latter, while in its opposite extreme it extends entirely below such shelf, in order 70 not to obstruct the descent of a sole down the latter. In its active stroke the packing-arm *w* rises erect through the slot *u*, intercepts the molded sole last precipitated from the lower platen, and, tilting such sole to a position at 75 right angles to the top of the shelf, deposits it against the last one of the pack, at the same time pushing forward the entire pack, and with it the ledge *v*, upon such shelf a distance equal to the thickness of the last sole deposited. 80

The mechanism for automatically feeding or advancing the soles in succession to the lower platen and against the bearers or stops *f f* consists of a flat plate, *S*, laid centrally upon the top of the table *B* and moved to and fro of 85 the latter by the following means: To the shaft *G*, before named, we secure at a suitable point a disk, *y*, in one end of which we form a cam-groove, *z*, into which groove extends a stud, *a*, secured to and extending laterally from the 90 lower end of an oscillating lever, *b*, which is pivoted, as shown at *c*, to a bracket, *d*, making part of the housing *A*, the upper end of the bar *b* being pivoted to the front end of a pitman, *e*, the rear end of such pitman being 95 in turn pivoted to the upper end of a vibratory arm, *f*, which is secured at its lower end rigidly to a horizontal rock-shaft, *g*, mounted in 100 bearings erected upon the top of the frame *A*. To the rock-shaft *g*, and centrally thereof, is 105 also rigidly secured the lower end of a bar or rod, *h*, the opposite end of which is pivoted to a rod, *h*, connected to the under side of the plate *S*. 110

Rotations of the shaft *G* and cam-disk *y* effect, through the agency of the lever *b*, pitman *e*, and arm *f*, rockings of the shaft *g*, and these rockings, through the aid of the rod *h* and rod *h*, impart rectilinear reciprocations to the feed-plate *S*. 120

To actuate the shipper-bar *i* in one direction against the stress of its spring *k*, and thereby spread the bearers or stops *f f*, we reduce the front end of the said bar *i* upon one edge, to an oblique bearing-surface or inclined plane, *i*, 130 against which a stud, *j*, extending from the plate *S* wipes, as such plate effects its rearward trav-

erse, the spring k , before named, serving to restore the lever to its normal position as fast as the stud recedes. The feed-plate S is confined to the table B and permitted to slide thereupon by a dovetailed spline secured to the under side of such plate, and received within a similarly-formed groove in a boss cast upon the under side of said table.

Preparatory to operating with this machine 10 a set or pile of soles is laid upon the table B , with their lower edges resting against the gage-plate r , and the lower sole opposite and ready to enter the throat s .

The operation of the machine is as follows, 15 presuming the various parts to be in the following position—that is, the arm w is in its lowest position beneath the top of the shelf Q , the feed-plate S is at its extreme rearward position, and the bearers $f f$ separated to their 20 full extent, in which case the stud j^2 bears against the straight surface of the shipper-bar i , the upper platen stands at its extreme highest position, ready to descend, and the pins $l m$ are separated to their fullest extent: The driving-shaft G being put in rotation, the feed-plate S begins, through the instrumentality of the cam-groove z , lever b^2 , shaft g^2 , and rods or pitmen $e^2 h^2$, the advance of the feed-plate, and such plate continues to advance toward the set of 25 soles until it has described a portion—say two-thirds, or thereabout—of its advance, and pushes the lower sole nearly over the lower platen, the stud j^2 meanwhile traveling along the straight portion l^2 of the edge of the shipper-bar i without effect upon the latter. The stud j^2 now reaches the inclined plane i^2 of the shipper-bar i , and travels along such incline as the plate S completes its forward traverse, (the spring k holding the bar i up to such stud,) the bars $O P$ 30 being thus forced together and the bearers $f f$ brought into immediate proximity to the ends or outer corners of the sole by the action of such spring k , the bearers in this position constituting stops or bearings to the sole, which 35 is advanced against them by the feed-plate. As the feed-plate completes its descent the upper platen, by the action of the crank H of the shaft G acting upon the pitman or rod M' , toggle $I I'$, and cross-head J , descends, and the pins 40 $m m$ descend upon the sole and clamp the latter between them and the lower pins, $l l$. The feed-plate S , by the continued rotation of the cam-disk y , now begins to return or retreat, the groove z of such disk being preferably of 45 such form as to aid in effecting this retreat on the first half of such retreat very quickly, in order that the spreading or opening of the bars $O P$ and the retreat of the bearers $f f$ away from the platen N may be effected before the 50 descent of the sole upon said platen, as otherwise the bearers would obstruct the upper platen, it being observed that as the said feed-plate retreats its stud j^2 wipes against the inclined plane i^2 of the shipper-bar i , and by 55 crowding such bar to one side spreads the said bars $O P$. During the first part of the re-

treat of the feed-plate the upper platen, M , descends upon the lower one, N , and molds the sole between them, the pins $l l$ and $m m$ retreating and disappearing within their pockets, as stated. The feed-plate continues to retreat, and the upper platen, by the continued rotation of the crank H , begins its ascent, which continues until the pins $m m$ rise above the sole, when the latter, lifted from off the lower platen by the pins $l l$, drops from such pins upon the shelf Q , down which it slides until it brings up against the ledge v . The feed-plate now completes its retreat movement, and at the same time the upper platen rises to its highest point, while simultaneously with such movement the packer-arm w , by the action of the rod x and toggle-joint before named, rises to a position at right angles to the surface of the shelf Q , in its passage tilting the sole and packing it against the ledge v , at the same time advancing such ledge a distance equal to the thickness of the sole thus deposited against it.

We have stated that the cam-groove z aids in opening the bars $O P$ with a rapid movement, which is correct, as such groove retreats the feed-plate; but the pitch of the inclined plane i^2 of the bar i has greater effect, as the more acute its angle laterally of the table B the quicker will the spreading of the bars be effected.

We claim—

1. The combination, with the feed-plate and the two molding-plates of a sole-molding machine, of guides or stops automatically operating to intercept the advanced sole and determine its position over the lower platen and retreat before the two platens meet, substantially as described.

2. The combination, with the feed-plate and the two molding-plates of a sole-molding machine, of guides or stops operating automatically to intercept the advanced sole, and spring-impelled pins contained in pockets in the platens, and operating to clamp the sole before meeting of the platens, substantially as described.

3. The combination, with the feed-plate and the two molding-plates of a sole-molding machine, of yielding pins or bearers applied to both of said platens, and adapted as the platens closely approach each other to clamp the sole between them in position over the lower platen, while as the platens meet such pins recede until their heads are flush with the molding-surfaces of said platens, substantially as described.

4. The bars $O P$, pivoted to the table B , in combination with the feed-plate S and platen N , such bars being operated by the pitmen $n n$, connecting them with the shipper-bar i , and the latter operated in one direction by the spring k and in the other by the stud j^2 of the said feed-plate, substantially as described.

5. The bars $O P$, with their bearers $f f$, in combination with the platen M and feed-plate

S, said bars being pivoted at their rear ends to the table B, and opened or closed by suitable means, substantially as described.

6. The combination, with the feed-plate S and bars O P, pivoted at their rear ends to the table B, of the shipper-bar i, pivoted to such table and connected with the bars by the pitmen n, and forced out of its normal position to open said bars by the stud j² from the feed-plate acting upon an inclined plane upon the said bar i against the stress of the spring k, which serves to restore the said bar to its normal position, substantially as described.

7. The combination of the upper platen having spring-pressed pins l l, with the lower platen having spring-pressed pins m m, each pin being capable of receding under pressure into the body of its platen, but normally held in a protruding position by its spring, substantially as shown.

8. The self-adjusting gage-plate r, with the bevel t upon its lower edge, in combination with the table B, frame C, and feed-plate S, substantially as described.

9. The swinging arm w, in combination with the shelf Q and yielding ledge v, such arm being pivoted at one end to the under side of the shelf, and operated by the rod x and the link l of the toggle-joint, substantially as described.

10. The combination, with the table B, feed-plate S, gage-plate r, frame C, shelf Q, and ledge v, of a device operating automatically to tilt and pack against said ledge the soles precipitated in succession from the lower platen, substantially as described.

11. In combination with shelf Q, the yielding ledge v, attached thereto, substantially as set forth.

12. The table B, provided with inclined slots e e, in combination with the bars O P and adjustable pivots c c, substantially as and for the purposes stated.

13. In a sole-molding machine, the combination, with the molding-platens, of mechanism, substantially as described, for arresting the molded soles in succession as they are discharged from the platens, and packing the entire set thus discharged into a compact pile, substantially as explained.

In testimony whereof we affix our signatures in presence of two witnesses.
